[57] CLAIM

The ornamental design for a beverage can crusher, as shown and described.

DESCRIPTION

FIG. 1 is front elevational view of a beverage can crusher showing my new design;

FIG. 2 is a left side elevational view thereof;

FIG. 3 is a right side elevational view thereof;

FIG. 4 is a top plan view thereof; and

FIG. 5 is a bottom plan view thereof.

The rear elevation not shown is similar to the front elevational view shown in FIG. 1.
